(57) **CLAIM**

The ornamental design for a pneumatic tire, as shown and described.

DESCRIPTION

FIG. 1 is a top perspective view of a pneumatic tire according to our new design, it being understood that the tire pattern repeats circumferentially about the outer circumference.

FIG. 2 is a front elevational view thereof.

FIG. 3 is a rear elevational view thereof.

FIG. 4 is a right side elevational view thereof; and,

FIG. 5 is a left side elevational view thereof.

1 Claim, 5 Drawing Sheets
